UNITED STATES PATENT OFFICE.

HERMAN WALCH, OF FESSENDEN, NORTH DAKOTA.

WATER-ELEVATING APPARATUS.

Application filed November 3, 1925. Serial No. 66,572.

This invention relates to water elevating apparatus and particularly to that type wherein water is subjected to pressure as the lifting medium.

- 5 An object of the invention is to provide simple and efficient means for creating a vacuum or partial vacuum to be used for lifting the water which is subjected to atmospheric pressure.
- 10 Another object of the invention is the provision of a vacuum creating means combined with a water holding tank and further combined with means for controlling the vacuum creating means, the water outlet 15 valve mechanism and the vacuum destroying means.

Another object of the invention is the provision of means whereby the operation of all of the mechanisms may be automatically 20 accomplished.

A still further object of the invention resides in the combination with a vacuum tank of means for supplying a combustible gas thereto, and means for either manually 25 or automatically controlling the flow of the supply of gas.

With these objects in view the invention consists in the novel features of construction, combination and arrangement of parts 30 as will be hereinafter referred to and more particularly pointed out in the claims.

In the drawings:-

Figure 1 is a side elevation of the preferred form of the apparatus.

35 Figure 2 is an enlarged vertical sectional view of the apparatus taken through the vacuum tank thereof.

Figure 3 is a sectional view of a gas burner nozzle and valve used in the apparatus.

40 Figure 4 is a vertical transverse sectional view of the apparatus taken on the line 4-4 of Figure 2.

Figure 5 is a detailed sectional view of 45 a valve used in the apparatus.

Figure 6 is a vertical sectional view of a modified form of the apparatus.

Figure 7 is a vertical sectional view of 50 still another modified form of the apparatus.

As illustrated in the accompanying drawings the apparatus includes a pressure and water tank 2 within which is created the vacuum or partial vacuum and through 55 which the water is elevated from a well or cistern. The tank is preferably of metal

and is made air tight under the water elevating action of the apparatus. The tank is provided at its top wall 5 with a hand opening 6 which is normally closed by a 60 plate 8 secured in position by said screws or bolts 9, the joint being suitably packed by a gasket of usual form.

The well or cistern indicated as 4 is in communication with the bottom wall 10 of the tank through a water feed pipe 11, the inlet end 12 of which is provided with a check valve 14 and submerged in the body of water 15 to a suitable distance below the level of the surface thereof.

65 A gas generator tank 18 is used in the apparatus and any kind of gas may be generated in the said tank. The tank is provided with a pressure gage 19 of usual construction and a pipe 20 connects the 70 tank 18 with the tank 2 through a wall 21 thereof and is secured by a packing gland 22. The end of the pipe 20 which is located within the tank 2 is provided with a burner nozzle 24. The pipe 20 is further connected 75 with a main control valve 25.

80 Within the tank 2 is arranged a float 26, the arm 28 of which is pivoted at a point between its ends as at 29 upon a bracket 30 supported upon the inner surface of the 85 side wall 21 and secured to the said wall by rivets 32. The burner nozzle 24 which is adjacent the valve 25 may be automatically supplied with the gas by means, which will now be described, for controlling the action 90 of the said valve. A pair of chains or cables 34 are connected at their upper ends with the outer extremities of a valve rocker arm 35 and at their lower ends with the float arm 28 on opposite sides of the pivot 29 as at 95 36 and 38. The arrangement is such that when the float is in an elevated position the supply of the gas to the burner nozzle will be substantially cut off due to the closing of the valve and when the float moves to a lower 100 position the valve is opened partially to permit vigorous burning of the gas at the nozzle. As the gas is burned at the nozzle the oxygen in the air contained within the tank 2 is consumed and thus a vacuum or partial 105 vacuum is created within the tank 2.

110 For the purpose of automatically and periodically discharging the water which has been drawn into the tank 2 and simultaneously destroying the vacuum or partial vacuum or for maintaining the vacuum and shutting off the exit of water from the tank,

I provide a reciprocatory valve rod 40 provided intermediate its ends with an elongated yoke 41 within which operates the float arm 28, said valve rod being provided on its upper end with a valve 42 arranged outside of the tank and cooperating with a valve seat 44 on the top wall thereof, the lower end of the rod being also provided with a valve 45 which is adapted to cooperate with a valve seat 46 of a water outlet pipe 48 entering the tank through the bottom thereof.

For the purpose of more clearly understanding the operation of the apparatus, it will be assumed that the tank has been filled due to the creation of a vacuum therein by the consumption of the oxygen of the air contained therein.

At this time the float will be in an elevated position and the arm 28 through its engagement with the upper end of the yoke 41 will have raised the valve rod 40, unseating the valves 42 and 45. Thus the vacuum is broken and the water may flow from the tank 2 through the outlet pipe 48. In its elevated position, the burner nozzle valve will be substantially closed. As the water leaves the tank, the float will fall. When the float reaches its lowest position its arm will engage the lower end of the yoke and thus the rod 40 is moved in a downward direction and the valves 42 and 45 are closed against their respective seats and the operation of elevating the water is repeated.

From the foregoing description of the construction and operation of my improved device, it will be seen that I have provided a

simple, inexpensive and efficient means for carrying out the objects of the invention. While I have particularly described the elements best adapted to perform the functions set forth, it is obvious that various changes in form, proportion and in the minor details of construction may be resorted to, without departing from the spirit or sacrificing any of the principles of the invention.

Having thus described my invention, what I claim is:—

1. A water elevating apparatus comprising a tank having a valve controlled air inlet, a valve controlled burner located within the tank, a float pivotally mounted in the tank, means operatively connecting the float with the burner valve to open and close the same as the float moves, means connecting the float with the valve of the air inlet, means for leading water into the tank and means for leading water out of the tank.

2. A water elevating apparatus comprising a tank having an air inlet opening, a valve member located exteriorly of the tank and adapted to close over said opening, a float pivotally mounted in the tank, a valve controlled burner located within the tank, means operatively connecting the valve of the burner with the float to open and close the valve of the burner upon the movement of the float, means for permitting water to enter the tank and means for leading water out of the tank.

In testimony whereof I affix my signature.

HERMAN WALCH.
